United States Patent Office

Des. 224,949
Patented Oct. 24, 1972

224,949

BROOM COVER

Mary J. Schildknecht, 6202 Upper Hunter Trace Road,
Louisville, Ky. 40216

Filed Dec. 7, 1970, Ser. No. 26,333

Term of patent 14 years

Int. Cl. D4—01

U.S. Cl. D4—4

Fig. 1.

Fig. 2.

FIG. 1 is a front view of a broom cover showing my new design, the opposite side being a mirror image of the side shown.

FIG. 2 is a side view of the broom cover shown in FIG. 1.

I claim:

The ornamental design for a broom cover, as shown and described.
